(57) **CLAIM**

The ornamental design for a weight-bearing bracelet, as shown and described.

DESCRIPTION

FIG. 1 is a front perspective view of a weight-bearing bracelet, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top view showing the weight-bearing bracelet in a use state;

FIG. 10 is a top view showing the weight-bearing bracelet in a split state; and,

FIG. 11 is an enlarged detail view of area 11 in FIG. 1.

The broken lines in the drawings illustrate the portions of the weight-bearing bracelet, which form no part of the claimed design.

The dash-dot-dash broken lines encircling the enlarged views are for annotative purposes only and form no part of the claim thereof.

1 Claim, 11 Drawing Sheets
